UNITED STATES PATENT OFFICE.

ROBERT ATHELSTAN MARR, OF BLACKSBURG, VIRGINIA, ASSIGNOR TO WILLIAM J. MOORE, OF WASHINGTON, DISTRICT OF COLUMBIA.

DEVICE FOR DRYING THE HAIR.

931,881.

Specification of Letters Patent. Patented Aug. 24, 1909.

Application filed March 26, 1909. Serial No. 485,998.

To all whom it may concern:

Be it known that I, ROBERT ATHELSTAN MARR, of Blacksburg, in the county of Montgomery and in the State of Virginia, have invented a certain new and useful Improvement in Devices for Drying the Hair, and do hereby declare that the following is a full, clear, and exact description thereof.

As is well known, the operation of drying hair, especially when the hair is long, as in the case of women's hair, after washing or shampooing, is a tedious and annoying one, and as far as I am aware to the contrary, no satisfactory appliances have been put upon the market for performing this operation.

A satisfactory device for this purpose should be very simple in its construction and operation, so that it will not be easily gotten out of order, and will require no special skill in manipulating it, and it must perform the operation rapidly and thoroughly and with comfort and safety to the health of the user.

The object of my invention has been to produce a device fulfilling these requirements, and in the attainment of this object my invention consists in the hair-drying device having the characteristics of construction and operation substantially as herein-after specified and claimed.

Referring to the drawings, Figure 1 is a view partly in perspective and partly in side elevation of an apparatus embodying my invention; and Fig. 2 a longitudinal section of the device that is applied to the head.

Generally described, my invention as illustrated in the drawings comprises a member or part 10 for application to the head, and an air pump, or means for producing a flow or current of air through said member or part 10. The member 10 consists of a series of tubes 11 attached at one end to and radiating from a chamber 12, the tubes for the greater portion of their length extending in substantially the same direction, but diverging slightly toward their free ends, and bent on a simple curve so as to conform to the contour or curvature of the head on their inner or concave sides. The member or part 10, it will be seen, has the general appearance of the extended fingers of the hand, and as will be evident when thrust in the hair, will extend over quite a large surface.

In its outer or convex side, each tube has a series of air holes or perforations 13, so that the direction of air passing outward from

the tubes will be away from the head. As the tube is imperforate on the side next the head, it will be seen that when air is forced outward from the tubes, it will not blow against the scalp, and thus the discomfort and danger to health, which would result from this condition, are avoided. Moreover, in the operation of the apparatus by the blowing or discharge of air outward from the tubes, the outward direction or passage of the numerous jets or currents of air will cause the separation of the hair into strands, and thereby greatly facilitate the access of air to a great quantity of hair, and so hasten the drying operation. The accidental or inadvertent placing of the member 10 upon the head with the air holes turned next to the scalp is prevented by reason of the location of the air holes or openings on the outwardly curved or convex sides of the tubes, for by reason of the curvature of the tubes as described, the wrong application of the member 10 to the head, should it occur, will be at once discovered.

To constitute at the same time a handle, and a means of connection of the member 10 with the air pump or source of supply of air, I attach to the chamber 12 at the side opposite the side where the tubes are attached, preferably a metal tube 14 of suitable length to form a handle, and preferably of such weight as to counterbalance the weight of the hair-engaging tubes, so as to render more convenient or comfortable the handling of the member 10, and the outer or free end of said tube 15 is formed for the convenient connection of a flexible tube or hose 15 for connecting the member 10 with an air pump or a source of supply of air. In the drawings, I illustrate an air pump 16 operating upon the principle of the Sprengel pump, and having two tube connections 17 and 18, respectively, enabling at will the blowing or forcing of air outward from the air holes 13 of the hair-engaging tubes 11, or the drawing of air through said holes into the tubes.

A desirable mode of using my apparatus, is to place the tubes or hollow fingers 11 in the wet hair, and for a while to cause the air to flow inward through the tube holes or perforations 13, and thereby suck or draw into the tubes the moisture or water in or on the hair, and then when the water has been removed as far as is possible by this procedure, to reverse the flow of the air and cause it to

blow outward from the hollow fingers or tubes to effect the further drying of the hair by evaporation of the moisture thereon. While I prefer and claim as a part of my invention, this reversal of the flow of the air, I nevertheless do not restrict myself thereto, because in some cases it may not be necessary or desirable to do this, so that, for example, the device will be used by the discharge or emission of air from the tubes or hollow fingers into the hair.

The air may be heated, medicated or placed in any condition that may be found desirable. In its broadest aspects, it is of course immaterial by what means the air is caused to flow through the member that is applied to the head of the user.

While it is important that the air holes shall be in the outer sides of the tubes, it is not necessary that they be in the highest points of the tubes, as it may be preferable to locate them so that they stand at an angle, in which case they will be located on either side of the highest points of the tubes.

An important attribute or characteristic of my invention is the ability to thrust the fingers into the hair close to the head, so that the drying operation can be thus performed over all portions of the hair.

Having thus described my invention, what I claim is—

1. A hair-drying device comprising a series of tubes, having air holes or perforations on one side and imperforate on the opposite side, the imperforate side being placed next the head, and a support beyond which the tubes extend free, whereby they may be thrust into the hair close to the head.

2. A device for drying the hair comprising a chamber, a series of tubes radiating from said chamber, having air holes or perforations on one side, and imperforate on the opposite side, the imperforate sides of the

tubes being placed next the head, and a flexible connection between the chamber and a source of supply of air, said tubes projecting free from said other parts, whereby the tubes may be applied close to the head.

3. A device for drying the hair, comprising a series of curved tubes, the tubes being imperforate on their concave sides and perforated on their convex sides.

4. A hair-drying device comprising a chamber, a series of tubes radiating from said chamber, and curved to conform to the curvature of the head, and provided with air holes or perforations, said tubes being imperforate on their concave sides.

5. In a hair-drying apparatus, the combination of a member comprising perforated tubes for application to the head, said tubes being imperforate on one side, which side is placed next to the head, a support for the tubes beyond which the tubes extend free, whereby they may be thrust into the hair close to the head, and means for producing a flow of air alternately in either direction through said tubes.

6. In a hair-drying apparatus, the combination of a member comprising perforated tubes for application to the head, the tubes being imperforate on one side, that side being placed next the head, a support beyond which the tubes extend free, whereby they may be thrust into the hair close to the head, means for producing a flow of air, and reverse connections between said means and the tube for causing a flow of air therethrough in opposite directions.

In testimony that I claim the foregoing I have hereunto set my hand.

ROBERT ATHELSTAN MARR.
